UNITED STATES PATENT OFFICE.

KARL ENGEL, OF ARLINGTON, MASSACHUSETTS, ASSIGNOR TO UNITED SHOE MACHINERY COMPANY, OF PATERSON, NEW JERSEY, A CORPORATION OF NEW JERSEY.

SHOE.

1,101,419.

Specification of Letters Patent. Patented June 23, 1914.

Application filed May 25, 1911. Serial No. 629,485.

To all whom it may concern:

Be it known that I, KARL ENGEL, a citizen of the United States, residing at Arlington, in the county of Middlesex and State of Massachusetts, have invented certain Improvements in Shoes, of which the following description, in connection with the accompanying drawings, is a specification, like reference characters on the drawings indicating like parts in the several figures.

This invention relates to shoes and particularly to shoes of the type commonly termed sandals. One of the characteristics of sandals is the open formation of the upper, and in a common type of sandal the tongue is disposed in a comparatively large opening in the front of the upper and an ankle strap passing through a loop in this tongue serves to hold the sandal upon the foot. The appearance of the sandal upon the foot and also the comfort of the wearer depend to a large extent upon the position of the tongue over the foot. With the ordinary construction of sandal, the tongue is apt to slip to one side or the other of the middle of the opening in the front of the upper, or to one side or the other of the position in which it is intended to be maintained, thus detracting from the appearance of the sandal upon the foot and also frequently causing discomfort to the wearer.

An object of this invention is to provide a sandal which can be manufactured without additional expense, but which will be so constructed that the tongue will be confined positively in the proper relation to the strap and to the other parts of the shoe upper.

The invention is illustrated in the accompanying drawing, in which a sandal embodying the invention is shown in perspective.

The sandal shown in the drawing is of the stitch-down type and comprises a sole 2, an upper 4 having an outturned flange 6 attached to the sole 2, the upper being provided with ventilating openings 8 and a large opening in the front in which is located the tongue 10. The sandal is held upon the foot by straps 12 and 14 which pass through loops 16 and 18, respectively, in the tongue 10, these loops being formed by mak-

ing substantially parallel slits in the tongue. The part of the tongue 10 through which the strap 12 passes, being comparatively wide, tends to resist lateral displacement and little difficulty is experienced in keeping this part of the tongue in proper position over the foot. On the other hand the part of the tongue through which the strap 14 passes, being more remote from the point of attachment to the upper and being comparatively narrow, would be easily displaced were it not for the novel interlocking of the tongue and strap provided by the present invention.

Referring to the drawing, it will be noted that the strap 14 is of a width somewhat greater than the opening in the loop 18 in the tongue 10. In order, therefore, to hold the strap and tongue in substantially a fixed relation to each other, a notch 20 is provided in the strap, this notch interlocking with the loop 18 to prevent the strap 14 from slipping through the loop.

It will be understood that the invention is not limited to the provision of a single notch 20, but that if desired a number of notches may be provided to permit relative adjustment of the strap and loop, and if desired a notch may be also provided to engage the lower end of the loop.

Having described my invention, what I claim as new and desire to secure by Letters Patent of the United States is:—

1. In a shoe, a tongue and a strap, one of said parts being provided with an integral loop of fixed dimensions formed by making substantially parallel slits in said part and the other part being provided with a notch arranged to interlock with said loop, the width of said last mentioned part upon either side of said notch being greater than the length of said slits.

2. In a shoe, a tongue and a strap, said tongue being provided with an integral loop of fixed dimensions and the strap being provided with a notch arranged to interlock with said loop, the width of said strap upon either side of said notch being greater than the opening in said loop, whereby said strap when brought into proper relation to said loop automatically springs into interlocking engagement therewith.

3. A sandal or shoe comprising an upper

having an opening in the front, a tongue located in said opening, an ankle strap bridging said opening, said tongue being provided with an integral loop and said ankle strap being wider than the length of said loop and being provided with a notch arranged to interlock with said loop.

In testimony whereof I have signed my name to this specification in the presence of two subscribing witnesses.

KARL ENGEL.
